CLAIM

The ornamental design for a document holder, as shown and described.

DESCRIPTION

FIG. 1 is a front-top perspective view of a document holder showing my new design;

FIG. 2 is a front-bottom perspective view thereof;

FIG. 3 is a rear-top perspective view thereof;

FIG. 4 is a rear-bottom perspective view thereof;

FIG. 5 is a rear elevational view thereof;

FIG. 6 is a front elevational view thereof;

FIG. 7 is a right side elevational view thereof;

FIG. 8 is a left side elevational view thereof;

FIG. 9 is a top plan view thereof; and,

FIG. 10 is a bottom plan view thereof.

The evenly spaced dotted lines showing in FIGS. 1, 2, and 6 represent stitching and forms part of the claimed design. The remaining evenly spaced dashed broken lines in FIGS. 1-4 and 6-9 are included for the purpose of showing portions of the document holder that form no part of the claimed design.
